UNITED STATES PATENT OFFICE.

JESSE S. FLEISCHER, OF BALTIMORE, MARYLAND, ASSIGNOR TO LIBERTY MANUFACTURING CO., A CORPORATION OF MARYLAND.

DISPLAY SAMPLE.

Application filed December 30, 1922. Serial No. 609,897.

To all whom it may concern:

Be it known that JESSE S. FLEISCHER, a citizen of the United States, residing at Baltimore, in the State of Maryland, has 5 invented certain new and useful Improvements in Display Samples, of which the following is a specification.

This invention relates to a dummy-display-sample and has for its object to provide 10 a dummy garment-sample which will convey to an observer the exact style and appearance a complete garment will have when folded and placed on sale but which in reality dispenses with the greater portion 15 of a complete garment and its corresponding bulk of material.

Manufacturers frequently have a line of 20 garments embracing a hundred or more styles, and difficulties are experienced by salesmen when traveling with a line of samples including so many styles. In many 25 instances the manufacturer has outlets for his product through the jobbing trade, and if his line embraces a large number of styles, it frequently happens that the jobbing salesman has such a variety of merchandise to 30 sell that he must either entirely dispense with the samples of the manufacturer's line or carry only a few of the styles on the road with him. This elimination of or reduction 35 in the number of styles by the jobbing salesman materially decreases the sales of the manufacturer and the present invention is directed to a dummy display-sample that will overcome the difficulties pointed out.

The object therefore of the present invention is to provide a display-sample structure that will accurately display a style of garment but which will occupy but one-third or one-fourth the space of an ordinary 40 garment sample whereby the salesman may carry complete line of styles, which complete line may be packed in, say one trunk, as against three trunks for the same number 45 of samples as heretofore. This saving in space is very pronounced when the line of samples relate to night gowns of outing material which is very bulky, as it is in the business in which applicant is engaged.

50 The result of the invention is that not only will much less space be required for packing, but a considerable reduction in the baggage expense-account will be effected.

The invention is illustrated in the accompany drawing, wherein,

55

Fig. 1 shows one form of sample structure in perspective wherein the invention is embodied.

Fig. 2 illustrates a cross-sectional detail 60 through the same,—the section being taken on the line 2—2 of Fig. 1, and

Fig. 3 shows another cross-sectional detail 65 through the structure, as the same would appear if cut on the line 3—3 of Fig. 1.

Referring to the drawing the specimen 70 therein disclosed in Fig. 1, has the appearance of a complete folded garment,—presumably a style of night-robe, but in reality it is not a garment but only a dummy display-sample.

The display-sample shown comprises a front fabric part 5, and a back fabric part 6 which are united by a seam 7 across the top. The parts 5 and 6 are secured together along opposite sides by seams 8 and are permanently stitched together across the bottom by another seam 9. It will thus be understood that the front and back parts are stitched together on all four sides and 75 form a bag-like structure.

The front fabric part 5 is provided with a central placket 10 with buttons 11 and button-holes 12 and in this particular instance a collar structure 13 is shown attached to the back and the front fabrics, although 85 many styles of a line omit the collar. The collar is therefore not essential and may be omitted.

In this instance the front and rear of the display sample are formed with a yoke-like 90 construction 14 and 15.

To complete the display sample, the same is provided with sleeve-ends 16 and cuffs 17 which are secured in the side seams 8 and are folded over upon the front to convey 95 the impression of a complete garment folded.

The complete display sample has every appearance of a folded garment and serves 100 all the purposes of a complete sample garment while it avoids the bulk and thickness of a complete folded garment because it omits the skirt portion which the complete garment would have, and occupies but a fraction of the space required for a complete garment. Because of its permanently 105

stitched-together folded parts, the sample structure will retain its shape, though repeatedly handled, and materially facilitates the arrangement of the samples by the salesman for display or their packing away for transportation.

It is believed to be obvious that a sample constructed as shown and described herein will occupy so little space that all the styles 10 of a complete line may be readily carried without overloading the salesman with excess baggage.

Having described my invention, I claim,—

1. A display garment-sample having a 15 fabric front and a fabric back,—the fabric front having shoulder and neck portions and the fabric back having shoulder and neck portions whereby the two portions will embody all the neck and shoulder features of 20 a garment,—said front and back fabric portions being permanently secured together along their upper edges from the neck-opening to the opposite side-edges and said two portions also being permanently secured 25 together along the opposite sides and across the bottom edges thereof whereby the sample of two fabric thicknesses will display both the upper front and upper back portions of what appears to be a folded-skirted 30 garment.

2. A display garment-sample having a front and back each of which is formed of

fabric and each being united along the upper edges to form neck and shoulder seams said front and back portions having their side 35 edges united from the shoulder seams to their lower edges and also being united across the bottom edge from one side edge to the other and imitation sleeves secured in the opposite side edges of the front and 40 back at a point considerably below the shoulder seams and said imitation sleeves extending across the front fabric parts.

3. A display garment-sample having a back fabric piece and two front fabric pieces 45 with a pocket formed by said two front pieces of fabric said back and front fabric pieces having a neck-opening formed therein and being united at their upper edges to produce the appearance of shoulder seams,— 50 one front piece and the back piece being secured together along one side edge from the shoulder seam down to the lowermost edge, the other front piece and the back piece being secured together along the other side 55 edge of the back from the shoulder seam down to said lower edge and the two front pieces and the back piece being secured along their lower edges from one side to the other and crosswise of the lower end of 60 the placket and an imitation sleeve-end secured in each side edge.

In testimony whereof I affix my signature.

JESSE S. FLEISCHER.
